(57) **CLAIM**

The ornamental design for spectacle frame as shown and described.

DESCRIPTION

FIG. 1 is a front view of spectacle frame;

FIG. 2 is a rear view thereof;

FIG. 3 is a top view thereof;

FIG. 4 is a bottom view thereof;

FIG. 5 is a left view thereof; and,

FIG. 6 is a perspective view thereof.

(Continued)

The right side view of spectacle frames is omitted because it is a mirror image of the left side view of spectacle frame.

1 Claim, 3 Drawing Sheets

Related U.S. Application Data

having an international filing date of Apr. 6, 2020, now Pat. No. Des. 954,814.
